Inventor
John A. Johnson

Samuel A. Miller
Attorney

UNITED STATES PATENT OFFICE.

JOHN A. JOHNSON, OF MINNEAPOLIS, MINNESOTA.

LETTER BOX.

Application filed July 11, 1921. Serial No. 483,880.

To all whom it may concern:

Be it known that I, JOHN A. JOHNSON, a citizen of the United States, residing at Minneapolis, in the county of Hennepin and 5 State of Minnesota, have invented certain new and useful Improvements in Letter Boxes, of which the following is a specification:

This invention relates to receptacles of the 10 deposit and collection type, and the primary object of the invention is to provide an improved letter box, in which the insertion of the mail into the box, as well as the withdrawal of the mail from the box will be 15 facilitated.

The great fault of the majority of the 20 mail boxes now on the market from the standpoint of the mail carrier is the difficulty experienced in the placing of the mail in the box, which results in a great loss of time. Generally the arms and hands of the mail carrier are filled with packages of letters to be delivered, leaving only a part 25 of one hand free for the insertion of the mail in the box. Now, if the slot in the box is narrow and the cover for the slot is in an inconvenient position and of such form that the same is hard to operate, the insertion of the mail in the box is rendered extremely 30 difficult. Often, too, the fastening members utilized for securing the box to the door or 35 other support projects in the box, which forms a stop for the letters, thus rendering the insertion of letters in the box still more difficult.

It is therefore another object of the invention to provide a mail box having its letter receiving slot disposed in a convenient position, and to have a novel cover for the 40 slot normally urged over the slot, which can be easily and conveniently operated by the back of the same hand of the mail carrier, utilized for inserting the mail through the slot, and to provide a novel means for 45 curing the box in position, without necessitating the positioning of the fastening members through the rear wall of the box.

A further object of the invention is to provide a mail box having a novel form for 50 permitting the convenient removal of the mail from the box, and a novelly constructed door for permitting the convenient removal of the mail from the box.

A still further object of the invention is to 55 provide an improved mail box of the above character, which will be durable and efficient

in use, one that will be simple and easy to manufacture, and one which can be placed upon the market at a reasonable cost.

With these and other objects in view, the 60 invention consists in the novel construction, arrangement and formation of parts, as will be hereinafter more specifically described, claimed and illustrated in the accompanying drawings, forming a part of this specification, in which drawings:

Figure 1 is a front elevation of the improved box.

Figure 2 is a vertical longitudinal section through the improved box, taken on the line 70 2-2 of Figure 1.

Figure 3 is a fragmentary vertical section taken on the line 3-3 of Figure 2.

Figure 4 is a top plan view of the improved box, showing the cover for the letter 75 receiving slot in its normal position.

Figure 5 is a similar view, showing the cover for the mail receiving slot in its open position.

Referring to the drawings in detail, where-in similar reference characters designate corresponding parts throughout the several views, the letter A indicates the body of the box; B, the novel closure for the mail receiving slot thereof; C, the novel removing 85 door; and D, the supporting means for the box.

The body A is preferably constructed of sheet metal, but can be made of any other desired material, and includes the side walls 90 10, the front wall 11, the rear wall 12, and the upper and lower walls 13 and 14. If so desired, the side walls 10 can be formed integral with the front wall 11. As shown the upper edge of the front wall 11 is provided 95 with an inwardly extending flange 15, which is adapted to be secured to the inner surface of the top wall 13. The rear wall 12 has its upper, lower, and side edges provided with outwardly extending flanges 16, which can be 100 secured respectively to the upper wall 13, to the lower wall 14, and to the side walls 10. These flanges strengthen and add rigidity 105 to the box. The lower wall 14 can be provided with upwardly extending side flanges 105 17, which can be secured to the side walls 10. The rear wall 12 is preferably positioned inwardly of the rear longitudinal edges of the side walls 10, in order to define the fastening flanges 18, which form 110 the means for supporting the retaining device D for the box. The lower wall 14 pref-

erably extends at an angle to the horizontal, so as to facilitate the removal of letters and packages from the box. The upper wall 13 is of arcuate configuration, and overlies the 5 upper end of the side walls 10, and extends outwardly of the front wall 11, so as to prevent rain, snow and the like, from running down the front face of the box. The lower end of the front wall 11 of the box is provided 10 with a relatively large opening 19, which is closed by the door C which will be hereinafter more fully described. The opening 19 is provided for the purpose of permitting the convenient removal of mail from 15 the box. The upper wall 13 of the box is provided with a relatively wide longitudinally extending slot 20, which constitutes the means for positioning the mail in the box.

20 The novel closure B for the body A is of a substantially U-shaped form, and includes the depending legs 22 and the connecting bight portion 23. The upper wall 13 of the box at each end of the mail receiving slot 25 20 is provided with transversely extending slots 24 for the reception of the legs 22 of the cover B. The legs below the top wall 13 are provided with the upwardly inclined wings 25, which form guides for the legs 30 22 and underlie the slots 24, when the cover is moved to its rearward position, as shown in Figure 5 of the drawings. The lower ends of the legs 22 can be provided with discs 26, which are adapted to receive pivot 35 bolts 27, carried by the side walls 10 of the body A. These pivot bolts or pins 27, can be connected in any preferred manner to the side walls 10, and to the legs 22 of the cover B. As shown the inner ends of these 40 bolts are countersunk in the legs 22 of the cover as at 28, so as not to interfere with the insertion of mail into the box. The longitudinal edges of the connecting or bight portion 23, of the cover B is provided 45 with depending front and rear walls 29 and 30, which are secured by means of flanges 31 to the legs 22. The legs 22 are provided with guard strips 32, which are adapted to overlie the guide slots 24 formed in the 50 upper wall 13 of the body A. These guard strips form means for preventing the entrance of rain or the like into the box. In order to limit the swinging movement of the cover B, an integral upstanding lip 33 is 55 formed on the rear wall of the slot 20, and the rear wall 30 of the cover B is normally held in engagement with this lip and over the mail receiving slot, by means of springs 36. These springs 36 are of the leaf type, 60 but it is to be understood that any other preferred form of spring may be provided. The upper end of the springs 36 are provided with hooks 37, which engage the rear edges of the legs 22. The intermediate 65 portions of the springs are coiled around the pivot bolts 27, and are disposed intermediate the side walls 10 and the legs 22. The lower ends of the springs 36 are provided with feet 38 which are extended through, and engage the rear wall 12. By arranging 70 the spring 36 intermediate the side walls 10 and the legs 22, a housing is formed for the same, which prevents the accidental displacement thereof.

75 The door C for the opening 19 include a flat plate 40, the side edges of which may be provided with guard flanges 41, if so desired. The upper edge of the plate 40 is provided with suitable hinged barrels, which register with hinged barrels 42 formed on the upper wall of the opening 19, and the aligned or registering hinged barrels receive the hinged pintle 43. This door C is preferably provided with a sight opening 44 which may be provided with a suitable 80 transparency 45. A depending lip 46 is also formed on the lower edge of the plate 40, and forms a handle, whereby the same can be readily raised or lowered. This door is normally urged to a closed position, by means 85 of a spring 47, which is coiled around the hinged pintle 43, and bears against the door C and the inner surface of the front wall 11. In order to protect the spring and the hinged 90 pintle and barrel from the elements, a suitable guard plate or eave 49 can be provided. As shown this eave or plate 49 extends transversely across the front wall 11, and overlies or extends outwardly of the door C. 95 While no lock has been disclosed for the door C, it is to be understood that any suitable type of lock may be provided therefor if so desired.

100 The supporting means D for the body A consists of a transversely extending strip 50, having legs 51, which can be bolted or riveted as at 52 to the flanges 18 formed on the side walls 10 and the side flanges 16 formed on the rear wall 12. This strip 50 is adapted to slip over the hook 53, which can be 105 secured to the door or other suitable support. The hook 53 can act as a permanent fixture, if so desired, and consists of the attaching base 54, which is held in position by means of a suitable screw 55. A forwardly 110 extending portion 56 is formed on the attaching base, and terminates in an upwardly extending resilient tongue 57, which is adapted to be forced into intimate engagement with the rear wall 12. This forms a 115 friction lock to prevent the accidental displacement thereof from the hook.

120 It can be seen that when the box is placed in position, the upper wall 13 completely houses the member D and hides the same 125 completely from view.

125 When it is desired to place a letter in the box, it is merely necessary to place the hand against the upper end of the cover B and force the same rearwardly, which will 130

pose the slot 20 to view. The letter can then be readily placed in the slot. Upon removal of the pressure from the cover B, the same will swing to its normal position, and 5 again overlie the slot 20 and protect the contents of the box from the elements.

When it is desired to remove the mail from the box, it is merely necessary to grasp the lip 46 and lift the plate 40 against the 10 tension of the spring 47. Owing to the inclination of the bottom wall 14, the removal of the mail from the box is facilitated.

From the foregoing description, it can be seen that a mail box has been provided of exceptionally simple and durable construction, which will permit of the convenient insertion and removal of mail to and from the box.

If so desired, the front wall 11 may be 20 provided with a suitable name plate 50 as clearly shown in Figure 1 of the drawings.

Changes in details may be made without departing from the spirit or scope of this invention; but,

25 I claim:

1. In a mail box, a body including a top wall having a mail receiving slot formed therein, and a pair of transversely extending slots arranged adjacent to the terminals of the mail receiving slot, a cover for the slot including a pair of depending legs and a connecting bight portion arranged to overlie the mail receiving slot, the legs being mounted for swinging movement in the 30 guide slots, means pivotally securing the legs to the body, and means engaging said cover for normally urging the connecting portion over said mail receiving slot.

2. In a mail box, a body including an upper wall and side walls, the upper wall having a longitudinally extending mail receiving slot formed therein, and a pair of transversely extending guide slots arranged adjacent to the terminals of the mail receiving 40 slot, a closure for the mail receiving slot including a pair of depending legs mounted for swinging movement in the guide slots, and a connecting portion arranged to normally overlie the mail receiving slot, and arranged in spaced relation to the upper wall, means pivotally securing the inner ends of the legs to the side walls of the box, and springs engaging said legs for normally urging the connecting portions over said 45 slot.

3. In a mail box, a body including an upper wall and side walls, the upper wall having a longitudinally extending mail receiving slot formed therein and a pair of 50 transversely extending guide slots arranged adjacent to the terminals of the mail receiving slot, a closure for the mail receiving slot including a pair of depending legs mounted for swinging movement in the guide slots, a 55 connecting portion arranged to normally

overlie the mail receiving slot and arranged in spaced relation to the upper wall, means pivotally securing the lower ends of the legs to the side walls of the box, springs engaging said legs for normally urging the connecting portion over said slot, and means for limiting the swinging movement of said connecting portion in relation to said slot. 70

4. In a mail box, a body including an arcuate top wall and side walls, the top wall 75 having a longitudinally extending mail receiving slot formed therein and a pair of guide slots arranged adjacent to the terminals of the mail receiving slot, a cover for the mail receiving slot comprising a pair of depending legs and a connecting portion, means pivotally securing the terminals of the legs to the side walls of the body, depending flanges formed on the longitudinal edges of the connecting portion, and an 80 upstanding flange formed on the rear wall of the mail receiving slot disposed in the path of said depending flanges of the connecting portion for limiting the swinging movement thereof in relation to said mail receiving slot. 85

5. In a mail box, a body including an arcuate top wall and side walls, the top wall having a longitudinally extending mail receiving slot formed therein, and a pair of 90 guide slots arranged adjacent to the terminals of the mail receiving slots, a cover for the mail receiving slot comprising a pair of depending legs and a connecting portion, means pivotally securing the terminals of the legs to the side walls of the body, depending flanges formed on the longitudinal edges of the connecting portion, and an 95 upstanding flange formed on the rear wall of the mail receiving slot disposed in the path of said depending flanges of the connecting portion for limiting the swinging movement thereof in relation to said mail receiving slot. 100

6. A mail box comprising front and rear walls, side walls, top and bottom walls, the top wall having a longitudinally extending mail receiving slot formed therein, and transversely extending guide slots arranged 115 adjacent to the terminals of the mail receiving slot, a cover for said mail receiving slot including a pair of depending legs mounted for swinging movement in the guide slots, means pivotally securing the terminals of the 120 legs to the side walls, wings formed on the forward edges of the legs below the top cover arranged to be moved in the path of the guide slots when the cover is swung on its pivots, a connecting portion for the legs 125 arranged to overlie the mail receiving slot, and guard strips carried by the legs arranged to normally overlie the guide slots.

7. A mail box comprising front and rear walls, side walls, top and bottom walls, rear- 130

wardly extending flanges formed on the side walls positioned beyond the rear wall, the upper wall overlying said flanges, a mail receiving slot formed in the upper wall, a 5 cover for said slot, a mail removing door formed in the front wall, and supporting means carried by said rearwardly extending flanges.

8. A mail box comprising a body includ-
10 ing side walls, front and rear walls, and top

and bottom walls, the rear wall being ar-
ranged inwardly of the rear edges of the side
walls, a mail receiving slot formed in one of
the walls, a cover for said slot, a mail remov-
ing door formed in one of the walls, a cross 15
supporting strip secured to the side walls
rearwardly of said rear wall, and a support-
ing hook arranged to engage said strip.

JOHN A. JOHNSON.
